UNITED STATES PATENT OFFICE.

JAMES B. KIRBY, OF CLEVELAND, OHIO.

WASHING MACHINE.

Application filed January 29, 1921. Serial No. 440,873.

To all whom it may concern:

Be it known that I, JAMES B. KIRBY, a citizen of the United States, residing at Cleveland, in the county of Cuyahoga and State of Ohio, have invented a certain new and useful Improvement in Washing Machines, of which the following is a full, clear, and exact description, reference being had to the accompanying drawings.

10 This invention relates to machines for the rapid and convenient washing of clothing and fabrics, especially for domestic use, and its objects are the provision of a simple and inexpensive machine whereby the clothing after having been thoroughly cleansed can be centrifuged, the provision of a machine of this character which can be shifted from its washing arrangement to its drying arrangement without waste of liquid; the 15 provision of a machine possessing a minimum number of parts, and one which is susceptible of easy and thorough cleansing; the provision of a machine of this character which will operate with the employment of 20 a minimum amount of cleansing liquid; the provision of a domestic centrifugal machine of a high degree of stability; while further objects and advantages of the invention will become apparent as the description proceeds.

25 In the drawing accompanying and forming part of this application I have illustrated one embodiment of my said invention but without intent to limit myself to the features of construction therein shown. Fig. 1 is a 30 vertical sectional view through my improved washing machine showing the parts in washing position; Fig. 2 is a similar view showing the parts in extracting position; and Figs. 3 and 4 are respectively bottom and 35 top views of said machine drawn to a smaller scale.

Describing by reference character the parts shown in these drawings, 1 represents a cylindrical sheet metal casing having projecting therefrom the hollow well 2. The bottom of this casing is defined by the plate 3 which constitutes slightly more than a semicircle and joins the wall 4 of the well, which is here shown as constituting a semi- 45 cylindrical chamber located at one side of the casing axis. Located in the angle between the walls 3 and 4 is the axle 5 from which project the arms 6 and 7, the former constituting a reinforcement for the wall 4 and the latter a reinforcement for the wall 5. Journaled in the axle 5 and in a bearing

8 formed at the outer end of the arm 6 is a shaft 10 whose inner end carries the foraminous cylindrical basket 11 and whose outer end carries the friction wheel 12. The 5 basket is detachably secured to the shaft by suitable means such as the nut 13 and is also preferably stiffened by radial ribs 14 although its detailed construction is not important. At its opposite end this basket is 10 formed with an inturned flange 15 terminating in a protected circular rim 16.

Carried by the outer end of the arm 6 is a bracket 18 having at its end a bearing 19, and journaled between this bearing and a 15 companion bearing formed in the wall of the bearing 8 is a radial shaft 20 on which is 20 slidably mounted the friction disk 21. Carried by the other arm, 7, is an electric motor 22 whose shaft is provided with a friction 25 plate 23. The disk 21 is located between and in contact with both the plate 23 and the wheel 12, and in this embodiment I have 30 shown the motor shaft as having sufficient end play to maintain driving contact at both points, a spring 24 being employed behind the motor shaft for assurance. I have 35 shown the axis of the plate 23 as located opposite the rim of the wheel 12 so that when the disk 21 is near the periphery of the 40 wheel the resultant speed will be small by reason of the relation of said disk to both plate and wheel, and so that when said disk is moved inwardly the resultant speed increases for both reasons.

90 The ends of the axle are formed with trunnions 25 which are pivoted upon a horizontal axis to the frame 26, 26, so that when the container is upright all the liquid will collect in the well 4 and when it is horizontal it will all run back into the container. The upper end of the container is formed 95 opposite the wall 3 with a fixed top-portion 27 which extends sufficiently high to prevent the overflow of the liquid, and the rest 100 of it is covered with a hinged or movable lid 28. I have shown a pin 29 and sector 30 for fixing the container in the desired position. I have also shown a lever 31 engaging the hub of the friction disk 21 to shift 105 its position and vary the speed of the basket.

For washing purposes the container is set in horizontal position and the basket rotated rather slowly with sufficient water to 110 submerge its lowest portion; when sufficiently washed the container is rotated to the position shown in Fig. 2, and the lever

31 shifted to high speed position; a speed of about 800 R. P. M. is very satisfactory, the weight of the liquid in the well forming a very efficient ballast and this without splash-
5 ing. The process can be repeated without waste of liquid until the liquid becomes fouled.

It will be understood that I do not restrict myself to the features of construction herein 10 illustrated which are susceptible of great variation within the scope of my invention, especially as to the design of the driving connections, and power arrangements. For example it is within my invention to employ 15 a gear arrangement which shall reverse the direction of revolution of the basket at stated times during the washing operation. Also the design and arrangement of the casing, well, and basket can be changed, and the 20 method of mounting so that I limit myself only as set forth in my claims which I desire may be construed as broadly as the prior art will permit.

Having thus described my invention 25 what I claim is:

1. In a device of the character described, in combination, a cylindrical casing provided with an eccentric well projecting from one end thereof, means pivotally supporting said 30 casing whereby said well may be moved into either a lower or higher position relatively to the rest of the casing, a foraminous basket journaled in said casing upon its own axis, and means for rotating said basket in all 35 positions of said casing.

2. In a device of the character described, in combination, a cylindrical casing having a semi-cylindrical well projecting eccentrically from one end, a foraminous cylindrical 40 basket mounted in said casing for rotation about its own axis, means pivotally supporting said casing so that said well may be caused either to receive or to discharge the washing liquid, an electric motor carried by 45 said casing, and driving connections between said motor and basket operable in all positions of said basket.

3. In a device of the character described, in combination, a cylindrical casing, a foraminous cylindrical basket mounted therein for rotation about its own axis, means supporting said casing for rotation about an axis which is perpendicular to its own axis, an eccentric well carried by said casing upon 55 the side which is raised adapted to receive liquid therefrom when the casing is upright and to return liquid thereto as the casing is returned to horizontal position, and means for rotating said basket in all positions of 60 said casing.

4. In a washing machine, in combination, a cylindrical, liquid containing casing, a shaft co-axial therewith journaled in and projecting through the bottom of said casing, 65 a foraminous cylindrical basket secured to

the inner end of said shaft, driving means operatively connected to the projecting portion of said shaft, a well carried by said casing at one side of said shaft, and means for tilting said casing so as to bring said basket 70 either vertical or horizontal with said well either lowermost or uppermost.

5. In a washing machine, in combination, 75 a cylindrical, liquid containing casing, a cylindrical, foraminous, clothes containing basket concentrically located inside the same and journaled upon their common axis, said casing having a closable opening at one point and said basket also having an opening, means for rotating said basket at different speeds, and means for rotating said casing upon a horizontal axis, said casing having at one side of its horizontal axis a well adapted either to receive the liquid from said casing or to return it to said casing depending 80 upon the position of the casing relatively to said last named axis.

6. In a washing machine, in combination, 85 a cylindrical casing, a foraminous basket mounted inside the same and revoluble about 90 its own axis, means pivotally supporting said casing on a horizontal axis, the axis of said basket being perpendicular to said pivot axis, an electric motor rigid with said casing and operatively connected to said 95 basket in driving relation, and a well carried by said casing and adapted to receive the liquid therein when the casing axis is upright.

7. In a combined washing and wringing 100 apparatus, in combination a cylindrical casing pivoted on a horizontal axis, a foraminous cylindrical basket rotatably supported inside said casing so as to be rotatable about its own axis, said axes being perpendicular 105 to each other, an electric motor carried by said casing, and variable speed driving mechanism operably connecting said motor to said basket in all positions of adjustment of said casing.

8. In a combined washing and wringing apparatus, in combination a supporting frame, a cylindrical casing, pivoted to said frame on a horizontal axis which is transverse to the axis of the casing, a shaft journaled to said casing in line with the axis thereof and perpendicular to said first axis, a foraminous cylindrical basket secured to said shaft inside said casing, an electric motor carried by the exterior of said casing at 115 one side of said horizontal axis, an eccentric well projecting from the end wall of said casing upon the opposite side of said horizontal axis, a driving wheel carried by said shaft outside the casing, and variable speed 120 driving devices operatively connecting said motor and wheel.

In testimony whereof, I hereunto affix my signature.

JAMES B. KIRBY,
